PAPER MACHINE

Karl Helge Tomlund, Karlstad, Sweden, assignor
to Aktiebolaget Karlstads Mekaniska Werkstad,
Karlstad, Sweden, a company of Sweden

Application August 30, 1939, Serial No. 292,576
In Sweden August 31, 1938

11 Claims. (Cl. 92—44)

It is well known that in paper-machines of the Fourdrinier type, and particularly those which run at high speeds, difficulties are caused when the pulp mixture is delivered through the pulp outlet nozzle from the head box to the wire-cloth, by foam or air bubbles being formed which afterwards cause thin and transparent spots in the paper. Attempts have been made to destroy such air bubbles by blowing hot air or steam against the paper web on the wire-cloth, or by spraying water on the same.

Such air bubbles are formed by the wire-cloth, which moves at a high rate of speed over the breast-roll, carrying along air from the angle or gap between the outlet nozzle and the upward moving portion of the breast-roll, such air being then mixed with the pulp mixture which is delivered by the outlet nozzle to the wire-cloth.

In order to obviate this disadvantage it has been proposed to provide below the outlet nozzle and in front of the upward moving portion of the breast-roll covered by the wire-cloth, a closed chamber in which a reduced air pressure is maintained, and to allow the wire-cloth to pass through the said chamber immediately before the wire-cloth arrives at the pulp outlet nozzle.

Such a chamber is an expensive structure, however, and it is often not possible—or only after making considerable changes—to adapt the same to old machines. Furthermore, it is difficult to effect the necessary tightness between the said chamber and the wire-cloth, since damage may easily be caused to the latter.

The present invention provides a considerably simpler solution of the problem of preventing air bubbles from being formed in the manner above explained.

The improvement according to the present invention is mainly characterized by the provision, in the angle or gap between the outlet nozzle and the upward moving portion of the breast-roll covered by the wire-cloth, and at the upper boundary wall of said angle or gap, of a device by means of which one or more jets of a gaseous or liquid medium of a pressure higher than the atmospheric pressure may be directed from the said boundary wall substantially tangentially to, and in a direction substantially opposite to the direction of movement of, the upward moving portion of the wire-cloth, so that a screen or curtain of fluid pressure medium which shuts off the gap from the outside, is formed between the said boundary wall and the wire-cloth.

The invention is illustrated in the accompanying drawing which shows a few constructional

forms of apparatus according to the invention. Fig. 1 shows a longitudinal section through the inlet end of a Fourdrinier machine, and Fig. 2 shows a vertical cross-section on the line II—II in Fig. 1. Fig. 3 shows to a larger scale a cross-section of the supply pipe for pressure medium, and Fig. 4 shows another construction of the supply pipe. Fig. 5 shows a construction using a baffle plate for spreading the jets of pressure medium, and Fig. 6 shows a construction having a movable baffle plate.

Referring to Figs. 1 and 2, the pulp mixture flows from a high-pressure breast-box 1 through an outlet nozzle 2 which extends across the entire width of the machine, out upon an endless wire-cloth 3 which runs over the breast-roll 4 which rotates at a high speed in the direction of the arrow 21, the wire-cloth passing closely below the lower lip 5 of the outlet nozzle. The fibres settle on the wire-cloth, while the water flows through the wire-cloth and is led away.

Ordinarily, the wire-cloth would, of course, carry along air from the angle or gap 1 between the breast-roll and the bottom 6 of the outlet nozzle which gap is open towards the outer atmosphere, and into the narrow space 8 between the wire-cloth and the lower lip 5 of the outlet nozzle, and past the mouth of the nozzle, so that air would thus reach the lower side of the web of pulp delivered by the outlet to the upper side of the wire-cloth on the breast-roll. The air thus brought along would be forced upward in the web of pulp and cause the air bubbles previously mentioned.

It is the object of the present invention to prevent air from being carried along in this manner and thus to prevent the formation of air bubbles in the web of pulp. For this purpose the two side walls 9 of the breast-box are continued downwards and are so formed that they adhere to the curvature of the breast-roll. These side walls may be provided with packing strips 10 forming interleaving seals with the wire-cloth on the breast-roll. According to the constructional form here illustrated, there is provided in the bottom 6 of the outlet nozzle which forms the upper boundary wall of the said angle, a groove 16 which extends across the entire width of the machine, and in said groove there is provided a pipe 11 for the supply of a gaseous or liquid medium having a higher pressure than the atmospheric pressure, such as air under pressure, which is admitted at 12, and the supply of which may be regulated by any suitable means such as a valve 13.

Intermediate the side walls 9 in which the pipe 11 is rotatably journaled, the pipe is provided with one or more apertures 14, slots or holes, arranged in such manner that said air under pressure flowing out through said apertures is directed substantially tangentially to the upward moving part of the wire-cloth, and in a direction substantially opposite to the direction of movement of the same.

Said air flowing out through the apertures in the pipe 11 forms an air layer or a screen or curtain of air, as it were, which closes the said angle or gap which is otherwise bounded by the side walls 9, 9, the bottom 6 of the outlet nozzle, and the wire-cloth 3 on the upward moving portion of the breast-roll 4, and prevents the air outside said screen or curtain from being carried along by the wire-cloth. The ejector action set up by the air jet or jets in the portion of said angle or gap on the inner side of the jets, also contributes to the air in the angle on the inner side of said air curtain tending to flow in the opposite direction to the wire-cloth, and also produces a pressure drop in the said portion of the gap and thus also in the abovementioned space 8, which obviously results in that no air bubbles can penetrate from the wire-cloth into the web of pulp delivered on the same against the atmospheric pressure prevailing above said web of pulp.

Secured to the pipe 11 is a suitable means, such as a lever 15 by means of which the pipe may be turned so as to adjust the direction of the jets of pressure air from the pipe more or less tangentially with relation to the wire-cloth.

The outflow aperture on the pipe 11 may, of course, consist of a single longitudinal slot in the pipe extending across the whole width of the machine. It is also possible to use a greater number of shorter longitudinal slots 14, and in such case these slots are preferably arranged in at least two rows and in such manner that the ends of the slots overlap or pass each other, as shown in Fig. 2. These slots 14 should also preferably be arranged in such manner, as shown to a larger scale in Fig. 3, that the jets from the slots converge, approximately at the point of tangency on the breast-roll as indicated in Fig. 1.

Instead of slots it is also possible to make the outflow apertures on the pipe 11 in the form of round holes 17, as shown in Fig. 4, which holes should also in this case be located in several rows, and which may be bored in different angles relatively to the axis of the pipe, so that the air jets will cross one another as indicated by the arrows in Fig. 4, and do not leave any intermediate spaces through which the outside air might possibly penetrate into the gap.

Viewed in cross section the said holes 17 may be arranged in the same manner as that above mentioned in connection with the slots 14, and as illustrated in Fig. 3, that is to say, so that the jets from the holes 17 converge approximately at the point of tangency on the breast-roll.

In order still more to facilitate the formation of an air screen or curtain without objectionable interspaces, when using a supply pipe 11 having outflow apertures in the form of slots or holes, there may be provided, as illustrated in Fig. 5, a baffle plate 18, which extends over the entire width of the machine, and which is parallel to the pipe 11 which also in this case may be rotatably journaled, against which baffle plate the air jets from the slots or holes are directed so as to spread the same, after which they are directed substantially tangentially to the upward moving

portion of the wire-cloth. In this case the slots or holes are preferably arranged in one row only.

Fig. 6 shows another constructional form of a spreading device in which the baffle plate 19 is rotatably mounted on the pipe 11 which may also be rotatably journaled. Suitable means, such as a lever indicated at 20, may be attached to the baffle plate 19 for adjusting the position of the same. This arrangement facilitates considerably the directing of the jets relatively to the breast-roll.

In other respects the constructional forms having spreading devices as shown in Figs. 5 and 6 conform to that shown in Figs. 1 and 2.

I claim:

1. In a paper-machine of the Fourdrinier type, the combination of a breast-roll, a wire-cloth running over said breast-roll, a breast-box, a pulp outlet nozzle on said breast-box for supplying pulp to said wire-cloth above said breast-roll, said outlet nozzle having a lower wall forming the upper boundary wall of an angle or gap between said outlet nozzle and the upward moving portion of said breast-roll, means enclosing said angle or gap at the ends of said breast-roll, and means located adjacent said upper boundary wall for directing at least one jet of a fluid medium, extending over substantially the entire width of said breast-roll, substantially tangentially to the upwardly moving portion of said wire-cloth and in a direction substantially opposite to the direction of movement of said wire-cloth.

2. In a paper-machine of the Fourdrinier type, the combination of a breast-roll, a wire-cloth running over said breast-roll, a breast-box, a pulp outlet nozzle on said breast-box for supplying pulp to said wire-cloth above said breast-roll, said outlet nozzle having a lower wall forming the upper boundary wall of an angle or gap between said outlet nozzle and the upward moving portion of said breast-roll, means enclosing said angle or gap at the ends of said breast-roll, a tubular chamber located adjacent said upper boundary wall and extending over substantially the entire width of said breast-roll, said chamber being provided with at least one outflow aperture extending in the longitudinal direction of said chamber and directed substantially tangentially to the upward moving portion of said wire-cloth and substantially opposite to the direction of movement of said wire-cloth, and means connected to said chamber for supplying a fluid under pressure to the same.

3. In a paper-machine of the Fourdrinier type, the combination of a breast-roll, a wire-cloth running over said breast-roll, a breast-box, a pulp outlet nozzle on said breast-box for supplying pulp to said wire-cloth above said breast-roll, said outlet nozzle having a lower wall forming the upper boundary wall of an angle or gap between said outlet nozzle and the upward moving portion of said breast-roll, means enclosing said angle or gap at the ends of said breast-roll, a tubular chamber located adjacent said upper boundary wall and extending over substantially the entire width of said breast-roll, said tubular chamber being provided with a number of outflow apertures consisting of slots extending in the longitudinal direction of said tubular chamber and arranged in several rows in such manner that their ends overlap one another, said slots being directed substantially tangentially to the upward moving portion of said wire-cloth and substantially opposite to the direction of movement of said wire-cloth, and means connected to

said chamber for supplying fluid pressure to the same, in excess of atmospheric pressure.

4. In a paper-machine of the Fourdrinier type, the combination of a breast-roll, a wire-cloth running over said breast-roll, a breast-box, a pulp outlet nozzle on said breast-box for supplying pulp to said wire-cloth above said breast-roll, said outlet nozzle having a lower wall forming the upper boundary wall of an angle or gap between said outlet nozzle and the upward moving portion of said breast-roll, means enclosing said angle or gap at the ends of said breast-roll, a tubular chamber located adjacent said upper boundary wall and extending over substantially the entire width of said breast-roll, said tubular chamber being provided with a number of outflow apertures consisting of holes which are arranged in at least two rows extending in the longitudinal direction of said tubular chamber and the direction of the axes of which form different angles to the axis of said tubular chamber, said holes being directed substantially tangentially to the upward moving portion of said wire-cloth and substantially opposite to the direction of movement of said wire-cloth, and means connected to said chamber for supplying a fluid under pressure to the same.

5. In a paper-machine of the Fourdrinier type, the combination of a breast-roll, a wire-cloth running over said breast-roll, a breast-box, a pulp outlet nozzle on said breast-box for supplying pulp to said wire-cloth above said breast-roll, said outlet nozzle having a lower wall forming the upper boundary wall of an angle or gap between said outlet nozzle and the upward moving portion of said breast-roll, means enclosing said angle or gap at the ends of said breast-roll, a pipe rotatably journaled about its axis near said upper boundary wall and extending over substantially the entire width of said breast-roll, said pipe being provided with at least one outflow aperture extending in the longitudinal direction of said pipe and directed substantially tangentially to the upward moving portion of said wire-cloth and substantially opposite to the direction of movement of said wire-cloth, and means connected to said pipe for supplying a fluid under pressure to the same.

6. In a paper-machine of the Fourdrinier type, the combination of a breast-roll, a wire-cloth running over said breast-roll, a breast-box, a pulp outlet nozzle on said breast-box for supplying pulp to said wire-cloth above said breast-roll, said outlet nozzle having a lower wall forming the upper boundary wall of an angle or gap between said outlet nozzle and the upward moving portion of said breast-roll, means enclosing said angle or gap at the ends of said breast-roll, a pipe rotatably journaled about its axis near said upper boundary wall and extending over substantially the entire width of said breast-roll, said pipe being provided with a number of outflow apertures consisting of slots extending in the longitudinal direction of said pipe and arranged in several rows in such manner that their ends overlap one another, said slots being directed substantially tangentially to the upward moving portion of said wire-cloth and substantially opposite to the direction of movement of said wire-cloth, and means connected to said pipe for supplying a fluid under pressure to the same.

7. In a paper-machine of the Fourdrinier type, the combination of a breast-roll, a wire-cloth running over said breast-roll, a breast-box, a

5 pulp outlet nozzle on said breast-box for supplying pulp to said wire-cloth above said breast-roll, said outlet nozzle having a lower wall forming the upper boundary wall of an angle or gap between said outlet nozzle and the upward moving portion of said breast-roll, means enclosing said angle or gap at the ends of said breast-roll, a pipe rotatably journaled about its axis near said upper boundary wall and extending over substantially the entire width of said breast-roll, said pipe being provided with a number of outflow apertures consisting of holes which are arranged in at least two rows extending in the longitudinal direction of said pipe and the direction of the axes of which form different angles to the axis of said pipe, said holes being directed substantially tangentially to the upward moving portion of said wire-cloth and substantially opposite to the direction of movement of said wire-cloth, and means connected to said pipe for supplying a fluid under pressure to the same.

8. In a paper-machine of the Fourdrinier type, the combination of a breast-roll, a wire-cloth running over said breast-roll, a breast-box, a pulp outlet nozzle on said breast-box for supplying pulp to said wire-cloth above said breast-roll, said outlet nozzle having a lower wall forming the upper boundary wall of an angle or gap between said outlet nozzle and the upward moving portion of said breast-roll, means enclosing said angle or gap at the ends of said breast-roll, a pipe rotatably journaled about its axis near said upper boundary wall and extending over substantially the entire width of said breast-roll, said pipe being provided with at least one outflow aperture extending in the longitudinal direction of said pipe, means connected to said pipe for supplying a fluid under pressure to the same, and a baffle plate extending over substantially the entire width of said breast-roll and located in such position relatively to said pipe that a jet of fluid under pressure issuing from said outflow aperture on said pipe against said baffle plate is deflected by the latter in a direction substantially tangential to the upward moving portion of said wire-cloth on said breast-roll and substantially opposite to the direction of movement of said wire-cloth.

9. A paper-machine as in claim 8, in which said baffle plate is adjustable relatively to said pipe.

10. In a paper machine having a non-perforated breast-roll rotating at comparatively high speed, the combination with a wire cloth running over said breast-roll, a breast box, a pulp outlet nozzle connected to said breast-box for supplying pulp to said wire-cloth above said breast-roll, said outlet nozzle having a lower wall forming the upper boundary wall of an angle or gap between said outlet nozzle and the upward moving portion of said breast-roll, of means enclosing said angle or gap at the ends of said breast-roll, and means located in close proximity to said upper boundary wall of said angle for directing at least one jet of air having a higher pressure than atmospheric pressure, over substantially the entire width of said breast-roll and substantially tangentially to, and in a direction substantially opposite to, the upwardly moving portion of said wire cloth.

11. A paper machine having a non-perforated breast-roll, a wire-cloth running over said breast-roll, a breast box, a pulp outlet nozzle on said breast-box for supplying pulp to said wire-

cloth above said breast-roll, said outlet nozzle having a lower wall forming the upper boundary wall of a chamber, another boundary wall which is formed by the upwardly moving portion of said breast-roll, end closures for said chamber, and means located in close proximity to said upper boundary wall for directing a screen of air

substantially tangentially downwardly to the upwardly moving portion of said wire-cloth over substantially the entire width of said breast-roll, to prevent air outside of said chamber from being carried into said chamber and into the pulp mixture by the movement of said wire-cloth.

KARL HELGE TOMTLUND.
